UNITED STATES PATENT OFFICE.

ADOLPH OTTO SCHAEFER, OF BROOKLYN, NEW YORK, ASSIGNOR, BY MESNE ASSIGNMENTS, TO ATLANTIC SERVICE COMPANY, INC., OF BROOKLYN, NEW YORK, A CORPORATION OF NEW YORK.

ATTACHMENT FOR SAWS.

1,339,139.

Specification of Letters Patent.

Patented May 4, 1920.

Application filed August 2, 1918. Serial No. 247,937.

To all whom it may concern:

Be it known that I, ADOLPH O. SCHAEFER, a citizen of the United States, and resident of Brooklyn, in the county of Kings and State of New York, have invented certain new and useful Improvements in Attachments for Saws, of which the following is a specification.

My invention relates to an improved attachment for saws, having reference more particularly to saws intended for use in butcher shops and other places where animal carcasses are cut up and parceled out for public use.

An object of my invention is to provide an attachment which can be affixed to the frame carrying the blade of the saw, by means of which the handle may be quickly and conveniently mounted on said frame and firmly secured thereto; and it is furthermore provided not only that the handle can be applied to the saw more successfully in the first instance, but it may with equal facility be replaced if broken with the minimum expenditure of time and effort.

In this specification I disclose a preferred form or embodiment of my invention, but reserve the right to alter the construction which is actually shown and described herein, especially as regards the shape, size and arrangement of parts, to the full extent permitted by the scope and spirit of my invention, in so far as the general meanings of the terms used in the appended claims define the same.

On the drawings,

Figure 1 is a side elevation of the frame and blade of a saw, with an embodiment of my attachment made fast to one end of

the same;

Fig. 2 is a sectional view on the line 2—2 of Fig. 1;

Fig. 3 is a view similar to Fig. 1, but illustrating also the handle of the saw engaging my attachment and made fast thereto; and

Fig. 4 is a top plan of what appears on Fig. 3;

Fig. 5 is a detached view of an attachment interposed between the saw blade and the handle.

Having reference to the drawings, I show at 1 the frame of a saw, carrying a blade 2. This frame is of the usual shape with its ends turned downward; and with the blade

2 retained in place by having its extremities 55 secured to the down turned ends of the frame in any suitable manner, at the end to which the handle 10 is to be applied the frame is provided with say, a couple of large openings 3, which give passage to the 60 screws or other rivets 11 by which the frame and the handle are to be held together.

My invention comprises as an essential element the attachment 4, which may be simply two pieces of metal or a single piece, 65 having preferably the shape or outline indicated particularly on Figs. 1 and 2, and secured by riveting or otherwise to the end of the frame 1 in which the openings 3 are located, rivets 4^a being shown. When applied to the frame 1, the two side plates constituting this attachment 4 engage the corresponding sides of the frame. The attachment 4 in the form illustrated may be of such shape that it extends the frame rearward at the top; constituting a supporting surface, adjacent the curve of the frame where it extends downward to meet the blade 2. At this upper portion of the attachment 4 is provided registering openings 70 5 in the two side plates thereof, which are round holes drilled through the said plates in alinement one with the other, and may pass through the frame 2 or not as most convenient, and are adapted to be brought 75 into line with the larger openings 3 in the frame 1. The openings 5 are thus provided for the upper bolt of the handle which is to be made fast to the saw by virtue of this attachment. As will be understood the two 80 side plates of the attachment 4 are of the same shape and occupy coincident positions when the attachment 4 and the frame are riveted to each other.

Below the openings 5 I provide both 95 parts of the attachment 4 with slots 6, so located that they will register with but extend across the openings 3 in the frame 1; that is, in each side plate of the attachment will be found as many pairs of oppositely disposed slots 6 as there are openings 3; which slots 6 in width correspond to the size of the rivet body 11, but in length equal the diameter of the openings 3, whose diameters shall be of predetermined 100 105 largeness to accommodate the possible variations in positions of the rivets 17 when two or more are employed, as is almost in-

variably the practice. These slots 6 will therefore in width correspond to the diameter of the openings 5 above them; and it is thus provided that when the handle is put on, the bolts or other fastening devices which it carries, can be passed through the openings 5, the slots 6 in the attachment and the openings 3 in the frame 2 without difficulty.

10 When the handle 10 is affixed to the saw as shown in Figs. 3 and 4, the rear end of the frame 1 carrying the attachment 4 is simply thrust into the slot 12 of the handle and the uppermost bolt or screw 11 is passed 15 through the openings 5 and made fast. The remaining bolts of the handle can then easily be passed through the wider openings 3 and the slots 6; and when all the bolts are tightened, the handle and the frame will be 20 made rigid with each other. The bolts 11 may have heads at one end and threads at the other to receive any suitable kind of nut to enable them to serve their intended purpose.

25 The bolt in the handle which passes through the openings 5 engages these openings snugly and fills the same entirely. Hence, any tendency of the handle 10 to move vertically upon the frame 1 is entirely 30 provided against; while other bolts 11 similarly carried by the handle passing through the slots 6 and openings 3 prevent the handle from turning about the upper bolt as a pivot. The handle is therefore firmly 35 secured in place.

The purpose of the openings 3 in this frame 1 is merely to provide clearance or passage through it; and these openings need not be made to correspond in size with the 40 bolts 11 in the handle or even be accurately located. Thus the expense and labor of boring through the frame 1 at precisely determined points, are avoided. The openings 3 only need to be far enough apart to 45 allow the bolts of the handle relating thereto to penetrate them after the attachment has been riveted to the frame and the handle is ready to be put on. Of course the slots 6 in the attachment must be located so 50 as to register with the openings 3 and be far enough from the rear edge of the attachment to allow the bolts of the handle to engage them properly and hold the handle securely and properly in place in 55 contact with the rear edge of the attachment. By this method, when the holes 3 are formed their location can be picked more or less by the eye of the operator; and in making the attachment 4, one is only required 60 to get the holes 5 and the slots 6 at the proper distance from the edge of the attachment 4 and have them of sufficient width with respect to the diameter of the screws 8. The slots 6 may be of greater or 65 less length, but they need not register

exactly with the openings 3; for so long as these slots and the openings 3 permit the bolts of the handle to go through from one side to the other after the proper bolt of the handle passes through the openings 5 the desired end is obtained.

The attachment 4 forms in effect a very cheap mounting device that enables the saw and the handle to be easily and readily assembled. It should be applied to the frame before the handle 10 is fitted on it; and then in case it becomes desirable to replace the handle, a new one can be affixed to the frame as quickly and effectively as the original handle was mounted thereon.

If desired it is obviously practicable to make the attachment 4 in two separate pieces, but, as a matter of manufacture, it is preferable to form this part by bending so as to fit over the frame 1 and engage both sides thereof in the general manner illustrated. When the attachment is thus formed out of one piece of metal looped at the top as shown in the drawings, the openings 5 will be inserted through the attachment as described, either through the frame of the saw or only through the two side walls of the attachment, as shown in Figs. 1 and 2. But if the side plates of the attachment are made in two separate plates, 95 they would not in that case need to extend over the saw frame top or even up to the top portion. In either event the hole 5 would not pass through the attachment at all, but through the frame of the saw alone. This would of course fulfil the requirements of my invention in the same manner as if the hole were located in the attachment, for the reason that the latter is rigidly fixed to the saw frame.

100 My improvement is illustrated in connection with the type of saw frame which has the cutting blade attached as a separable member. While this form is the preferred application of my device, it obviously may be affixed to a single saw blade, such for example as the familiar type used by cabinet makers and joiners. Furthermore, it is desired to employ my improvement with other kinds of cutting tools, in 110 which a handle is attachable to a steel blade.

Having described my invention, what I believe to be new and desire to secure and protect by Letters Patent of the United States is:

115 1. The combination with the frame of a saw having a blade affixed thereto, said frame of hard steel and also having relatively large openings adjacent one end, of an attachment for the frame to be affixed to said end, said attachment of softer metal having slots to be located adjacent said openings on both sides of the frame, the attachment being adapted to permit a

handle to be secured to the frame by bolts extending through said slots and said openings.

2. The combination with the frame of a saw having a blade affixed thereto, said frame made of hard steel and having a pair of relatively large openings in one end, an attachment of relatively soft metal to be secured to the frame at said end and providing extension thereof, said attachment having an opening, and slots to be located adjacent the openings in the frame on both sides of the latter, said attachment adapted to permit a handle to be secured to the frame by means of fastening devices extending through said slots and said openings in the frame and the attachment.

3. The combination with the blade of a saw, of an attachment for one end of the blade of hard steel, said attachment of relatively soft metal engaging both sides of the

blade, being adapted to engage a handle for the saw to be secured in place by fastening devices extending through said blade and said attachment.

4. The combination with the blade of the saw having relatively large openings in one end, of an attachment for the frame to be affixed to said end, said attachment having slots to be located adjacent said openings on both sides of said blade, the attachment being adapted to secure a handle to said blade by bolts extending through said slots and said openings.

Signed at Brooklyn, in the county of Kings and State of New York this 24th day of July, A. D. 1918.

ADOLPH OTTO SCHAEFER.
